The Lowell Manufacturing Company.

Letters Patent No 1808-Dated Aug. 11th 1863.

The schedule referred to in these Letters Patent and making part of the same.

To all whom it may concern:

Be it known that I, Elmir J. Ney, of Lowell, in the County of Middlesex and State of Massachusetts, have originated and designed a new Pattern for Carpets or other fabrics, of which the following is a full, clear and exact description, reference being had to the accompanying drawings, making part of this specification.

In corner 1 is one fourth of a large set figure resting on the dotted ground, which is enclosed by the frame 2, supporting the oblong figures 3, 3. In corner 4 is one fourth of a small solid block. 3 is a figure in the form of a palm leaf, to which is attached a branch of mottled leaves. 5, 5 are halves of rosettes from which extend branches of leaves. 6, at the side, is one half of a figure in the form of a cross, surrounded by a square frame with a scalloped border.

In corners 7 and 8 are fourths of figures similar to that of which 6 is one half. The frames of fig. 6 and corners 7 and 8, are connected by Etruscan bands.

Fig. 9 is one half of an octagonal block. Figs. 10 and 11, are palm leaves supporting small rosettes from which extend successions of broken leaves and sprigs.

The colors employed for the different portions of the design may be varied to suit the taste and wish of the manufacturer.

Claim.

What I claim as my invention and desire to secure by Letters Patent, is: the design or pattern for carpets or other fabrics, herein set forth.
